HANDLING SYSTEM FOR LEAF TOBACCO

William W. Michaux, Jr., Richmond, Va.

Application October 8, 1954, Serial No. 461,156

16 Claims. (Cl. 214—5.5)

This invention is concerned with the handling of tobacco leaves, and more particularly relates to an improved tobacco stick, to means for attaching tobacco leaves to the stick, and to an improved system of blending tobacco leaves in conjunction with such stick and loading means.

A conventional tobacco stick is simply a straight, solid wooden lath of a length suitable for supporting tobacco leaves during drying operations. When tobacco is harvested it is placed on such sticks for preliminary drying. Sometimes that is accomplished by pointing one end of the stick and spearing it through a series of tobacco plants. Generally, however, a string is looped around the stems of small groups of leaves to hang them along diagonally opposite sides of the stick, which not only takes time to do in the first place but also requires more time later in removing the pieces of cut string from the tobacco after the preliminary drying operation. After preliminary drying the tobacco is marketed and later re-dried in the form of tied-up bundles, known as "hands," on the same kind of sticks. In order to intermix the tobacco leaves for purposes of obtaining a uniform blend, it has become customary to station several persons along a line of moving sticks so that they can straddle successive hands of tobacco from different baskets on each stick as it passes; see my Patent No. 1,862,192. Since each hand must be manually spread apart and balanced on the stick, the straddling operation requires a considerable amount of manual labor in the course of preparing commercial quantities of tobacco.

The present invention provides means for power loading tobacco leaves on sticks, and a new form of tobacco stick adapted to be loaded quickly by such power means. The loader and stick are suitable for use with separate leaves of tobacco and can also be adapted for use with hands of tobacco. The stick is of generally U-shaped cross-section with a pair of inwardly turned flanges at the open end of the U to grip the stems of the tobacco leaves, and with increased thickness at the base of the U to give the stick strength against bending when it is supported at its opposite ends and also to hold the flanges rigidly against the stems. The stick is preferably of solid, unitary form, with a uniform cross-section from end to end, and it is thus adapted to be manufactured economically by extrusion of a suitable metal, such as aluminum. The loading apparatus has guide means for receiving the stick, and opposed loading means for receiving the stems of the tobacco leaves and propelling them forcibly into the slot of the stick. End-wise pressure on the outer end of the stick holds it in the machine and selectively controls the tightness and density of packing of the stems in the stick. The ease and speed of loading the stick is increased by means for automatically starting the machine's motor when the stick is initially thrust into the machine to a certain limit, and by means for automatically stopping the motor when the stick has become sufficiently loaded and as a result has been pushed back by the loading means beyond another limit.

The parts of the machine which load the stick are associated with a moving belt which supports the leafy

2

end of the leaves as the stems are propelled by the loading means into the stick. The belt also extends for a considerable distance to the rear of the loading members, so that the leaves can be placed on the belt and will then be carried without manual intervention into the loading means and thence into the stick. This arrangement contributes to hanging the tobacco quicker than heretofore, because the persons who place the tobacco on the belt merely lay it on the belt with the stems in an approximately correct position and do not have to take time to straddle the leaves approximately evenly on both sides of a stick, as has been necessary heretofore. As a result, less labor is required to load successive hands of different kinds of tobacco on the sticks.

Other advantages, objects and details of the invention will become apparent in the following detailed description of the present preferred embodiment of the invention shown, for purposes of illustration only, in the accompanying drawings. In the drawings:

Figure 1 is a top plan view of apparatus embodying the invention;

Figure 2 is a side view of the apparatus of Figure 1; Figure 3 is a front end view of the apparatus of Figure 1 (the left end as shown in Figures 1 and 2);

Figure 4 is an enlarged detailed view of part of the loading chains shown in Figure 2;

Figures 5 and 6 are top plan views of the upper and lower chains, respectively, shown in Figure 4;

Figure 7 is an enlarged detailed view, partially broken away, of the chain loading means shown in Figure 1, with associated switch mechanism;

Figure 8 is a side view, partially broken away, of the loading means shown in Figure 7, and also including the rear sprocket of the lower loading chain;

Figure 8A is a detailed view, partially broken away, of the receiving end of the tobacco stick shown in Figure 8, and the guide member abutting the receiving end of the stick;

Figure 9 shows an enlarged, partially broken-away section on the line IX—IX in Figure 1;

Figure 10 shows an enlarged, partially broken-away section on the line X—X in Figure 8;

Figure 11 is a side view of a tobacco stick embodying the invention, after being loaded in the illustrated apparatus; and

Figure 12 is an enlarged end view of the loaded tobacco stick shown in Figure 11 (as seen from either end).

Referring now more particularly to the drawings, there is provided a tobacco stick loading machine 10 having a fixed table 11 at its front end. The upper reach of an endless conveyor belt 13 slides over a table 14 toward the table 11, and passes around a front drive roller 15 located next to the rear end of table 11. The other end of belt 13 is trained around a rear idler roller 15'. A pair of endless loading chains 16 and 17 are mounted along one side of belt 13, the upper chain 16 being trained around a front drive sprocket 18, a rear idler sprocket 19 and a raised intermediate sprocket 20. The lower chain 17 is trained around a front drive sprocket 21 and rear idler sprocket 22, and preferably extends further back than chain 16 in order to cooperate with belt 15 in conveying tobacco leaves into the nip between the chains. The lower reach of chain 16 slides along an upper guide track 23, and the upper reach of chain 17 slides along a lower guide track 24, the guide tracks being mounted in fixed horizontal positions so that the chains 16 and 17 move horizontally in closely spaced opposed relation along one side edge of the belt 13 from about the middle of the upper reach of the belt to its front drive roller 15. Tobacco leaves laid across the rear end of the belt 13 with their stems projecting from the side of the belt, such as the leaf 25 shown in

Figure 1, are carried by the belt between the opposed portions of chains 16 and 17, which seize the stems and propel them into a tobacco stick 26.

The tobacco stick 26 is generally U-shaped in cross-section, with a channel 27 extending uniformly along its entire length. The width and depth of the channel are sufficient to allow tobacco stems to be moved into the interior of the stick and to be gripped securely between a pair of flanges 28 and 29 which extend toward each other along the mouth of the channel 27. The flange edges are square cornered along the interior of the channel, in order to oppose forces tending to pull the stems out of the channel transversely of the stick, but have smooth, straight surfaces lengthwise of the stick, in order to allow sliding movement of the stems in both directions lengthwise of the channel. When the stems of untied tobacco leaves are loaded into the stick, the slot is preferably about $\frac{3}{8}$ " wide, and the depth of the channel in the stick is about 1". The width of the channel 27 may be enlarged, preferably in the course of manufacture but alternatively by spreading apart a tobacco stick already made, to receive tied bundles of tobacco leaves, such as the usual "hands" of tobacco. The stick 26 has a uniform cross-section from end to end, and is adapted for manufacture from a suitable material, such as aluminum, by convenient forming means, such as extrusion through a die. The extrusion is cut into pieces of whatever lengths are required by conventional driers. The base of the U is thickened in order to enable the stick to remain rigid against transverse bending, and also against spreading apart of the flanges 28 and 29. I have found that the tobacco stems, which always are at least somewhat moist when loaded on the stick, have sufficient natural resilience to enable them to wedge securely into the channel 27, although the channel itself is unyielding against the pressure of the stems. After being dried on the stick the stems tend to retain the indentation made in them by the flanges 26 and 27, and consequently the dried stems remain in the stick during ordinary handling, although they may be drawn endwise along the channel and out of either end of the stick with relatively little effort. When made of extruded aluminum, for example, the stick is lighter than a conventional wooden tobacco stick of the same length, and has the further advantage of a much longer useful life because of its strength and resistance to deterioration and warping.

The machine 10 includes a guide bar 30 of L-shaped cross-section, which is mounted parallel to the chain guides 23 and 24 and serves to guide the tobacco stick 26 into position to receive stems carried along between the chains 16 and 17. The bar 30 projects forward of the drive sprockets 18 and 21 in order to facilitate guiding the entering end of the stick 26 when it is initially thrust into the machine. An upper guide bar 31 overlies the portion of stick 26 extending along the guide bar 30 to the rear of the drive sprockets 18 and 21. The stick 26 is thrust most of its length into the machine along bar 30, and when fully inserted the rear end of the stick projects a short distance forward of bar 30 to provide a grip for a person holding the stick, while the forward end of the stick abuts a combination stop and funnel member 32 mounted in the machine adjacent the sprocket 19. The member 32 is a piece of a stick like the stick 26 (Figure 8A), with its forward end aligned with the stick 26, and its slot progressively widened toward its rear end to facilitate funneling the stems of the leaves between the chains and into the channel 27 of stick 26. A board 33 extends at an angle to the pass line of the belt 13 for purposes of cooperating with the member 32 and to funnel the stems into the nip of chains 16 and 17. A vertical board 34 is mounted adjacent one side of belt 13, with the rear end of chain 17 therebetween, and extends between the slant board 33 and belt idler roller 15' to serve as an abutment for evenly aligning the ends of the stems when they are placed on belt 13.

A motor 35 drives the machine through a belt drive to a

pulley 36 keyed on a main drive shaft 37, which is keyed to the drive sprocket 21 for driving chain 17; to the drive roller 15 for driving belt 13; and to a pinion 38 meshing with a pinion 39 keyed on a shaft 40 keyed to drive sprocket 18 for driving chain 16. The belt drive roller 15, chain drive sprockets 18 and 21, and pinions 38 and 39 are all of the same effective diameter, and consequently the opposed reaches of the chains 16 and 17 move along at the same speed as each other and also at the same speed as belt 13, so that a tobacco leaf laid transversely across the belt 13 remains in substantially the same position on the belt 13 before and while its stem is seized between the chains 16 and 17.

The person who thrusts the stick 26 into the machine stands next to the front table 11 and in case of emergency can readily stop the motor 35 by operating a master switch on a central control panel 41. For purposes of normal operation the motor is automatically controlled by a starting switch 42 and stopping switch 43, both operated by the stick 26. The starting switch is located just forward of the rear sprocket 19, and has an arm 44 pivotally mounted at one end on a shaft projecting from the case of switch 40, and carrying at its other end a feeler-roller 45 which rides up on the entering end of the stick 26 when it is thrust into the machine all the way up to abutting relation with the member 32. When the roller 45 rides up on the stick 26 it swings the arm 44 against the action of a suitable biasing spring to complete an electric circuit and thereby starts the motor 35. The motor must continue to operate as the stick retracts from the machine, and the automatic switch circuit accordingly has conventional means for continuing the operation of the motor power circuit after the entering end of the stick 26 has withdrawn from beneath the roller 45, until such time as the switch 43 stops the motor (e. g., the switches 42 and 43 may be connected in series with the motor and a solenoid coil which, while energized, holds up the arm 44 until the circuit is broken by switch 43). Referring now to the automatic stopping switch 43, as the entering end of the stick 26 initially moves into the machine it engages a feeler roller 46 and thereby swings an arm 47 of the stopping switch 43, which arm is spring biased and located immediately to the rear of the forward sprockets 18 and 21. This cocks the stopping switch 43, so that when the entering end of the stick 26 is later withdrawn past feeler roller 46, the arm 47 swings back to its original position and thereby opens the power circuit of the motor 35 and stops the motor, thus completing its automatic operating cycle.

Although the machine starts and stops automatically, the person who thrusts the stick 26 into the machine exercises full control over the operation. The operator's hand grips the rear end of the stick and thrusts the stick endwise into the machine up to stop member 32. The effective spacing of the chains 16 and 17 is made less than the width of channel 27 between flanges 28, 29, so that the stick readily receives in its channel all the stems held between the chains when the stick is inserted. The motor then starts and the chains commence moving the stems along channel 27 toward the operator's hand, which closes around the channel a few inches from the rear end of the stick. As the chains 16 and 17 carry more and more stems along channel 27 toward the projecting end of the stick, the stems begin to compact in the projecting end of the stick to a degree controlled by the endwise pressure exerted by the operator in holding the stick in the machine. When the pressure tending to compact the stems exceeds a predetermined limit sensed by the operator, he allows the stick to begin to move back out of the machine, slower than the movement of the chains, and maintains a generally uniform endwise holding pressure on the stick, so that stems will continue to be compacted evenly in the increasing length of the projecting portion of the stick. Near the end of the retracting movement the stick is held long enough to compact the last stems away from the trail.

ing end of the stick, and then the stick is entirely withdrawn. The stems are thus packed inwardly of both ends of the channel 27 to facilitate hanging the loaded stick for drying or other operations. As the loaded stick is withdrawn the leaves on the stems packed in channel 27 pass from the belt 13 to table 11 and are there supported until the stick is carried away after being entirely withdrawn from the machine.

In the illustrated embodiment of the invention the channel 27 of the stick 26 was assumed to be $\frac{3}{8}$ " in width, and the effective gap between the opposed reaches of the chains 16 and 20 was assumed to be $\frac{3}{16}$ ", which dimensions are preferred for purposes of loading tobacco leaves which are not tied in "hands." In some cases it may be desired to load the sticks with "hands" of tobacco leaves which are to remain tied in separate bundles while on the sticks. In that event the width of the channel 27 should be enlarged, and the gap between the chains 16 and 17 should be correspondingly enlarged as far as the stick is concerned, this can be done by widening the gap 27 of existing sticks, or by making some of the sticks originally with a larger channel 27. In either case it is necessary to make a corresponding adjustment of the gap between chains 16 and 17, and for that purpose the upper guide bar 31 (which overlies the top of the stick 26 while in the machine) and the upper chain guide 23 are attached to common supporting cross-bar 48 (Figure 10) which is carried on adjustable brackets 49. The brackets 49 are bolted to vertical support posts 50, and the bolt openings 51 in the posts 50 are slotted vertically so that the bolts can be loosened and the brackets raised or lowered before resetting the bolts in the desired adjusted position. In that way the guide bar 31 is readily adjustable to accommodate different widths of tobacco sticks to be used in the machine, and the upper chain guide 23 is automatically adjusted at the same time to accommodate the stems to be loaded into such sticks.

The above-described machine 10 and stick 26 are further advantageous in connection with inter-mixing leaves from several baskets in order to obtain a uniform blend. For that purpose baskets of tobacco are brought to the positions indicated in dotted squares 52 in Figure 1, along the side of belt 13 opposite to the stem abutment board 34. The tobacco may be in stacks of separate leaves or tied in "hands," but in any event a person at each basket lays the tobacco from his basket across the belt 13 in gaps between the tobacco laid on the belt from the other baskets, so that the tobacco from the various baskets is intermixed. The belt 13 carries the inter-mixed leaves to the chains 16 and 17, which load the leaves into the stick 26. Successive sticks 26 are thus loaded with generally uniform sampling from the baskets, ready for the usual redrying operations. The rear extension of belt 13 can be made long enough to accommodate any desired number of basket stations, which can be increased to the extent necessary to keep the belt 13 loaded to match any predetermined rate of loading of successive sticks 26. Since the sticks can be machine-loaded very rapidly, the operations as a whole can be carried on at a sustained high speed.

While a present preferred embodiment and method of practicing of the invention have been illustrated and described, it will be recognized that the invention is not limited thereto but may be variously embodied and practiced within the scope of the following claims.

I claim:

1. Apparatus for loading the stem ends of tobacco leaves into a channeled stick, comprising a conveyor adapted to support tobacco leaves laid transversely across the conveyor with their stem ends projecting from one side thereof, guide means for positioning a channeled stick adjacent and parallel to part of said one side of the conveyor with the channel of the stick open toward the conveyor, gripping members movable along a path between

the guide means and said part of the conveyor and adapted to seize intermediate projecting portions of the leaves on the conveyor and to propel their stem ends along the channel of a stick positioned by the guide means, and means connected to drive the conveyor and gripping members in the same direction.

2. Apparatus for loading the stem ends of tobacco leaves into a channeled stick, comprising a conveyor adapted to support tobacco leaves laid transversely across the conveyor with their stem ends projecting from one side thereof, guide means for positioning a channeled stick slidably endwise in the guide means adjacent and parallel to part of said one side of the conveyor with the channel of the stick open toward the conveyor, gripping members movable along a path between the guide means and said part of the conveyor and adapted to seize intermediate projecting portions of the leaves on the conveyor and to propel their stem ends along the channel of a stick positioned by the guide means, and means connected to drive the conveyor and gripping members in the same direction.

3. Apparatus for loading the stem ends of tobacco leaves into a channeled stick, comprising a conveyor adapted to support tobacco leaves laid transversely across the conveyor with their stem ends projecting from one side thereof, guide means for positioning a channeled stick slidably endwise in the guide means adjacent and parallel to part of said one side of the conveyor with the channel of the stick open toward the conveyor, gripping members movable along a path between the guide means and said part of the conveyor and adapted to seize intermediate projecting portions of the leaves on the conveyor and to propel their stem ends along the channel of a stick positioned by the guide means, a motor connected to drive the conveyor and gripping members in the same direction, a switch operable to start the motor, and switch control means responsive to insertion of a stick in the guide means to cause the switch to start the motor.

4. Apparatus for loading the stem ends of tobacco leaves into a channeled stick, comprising a conveyor adapted to support tobacco leaves laid transversely across the conveyor with their stem ends projecting from one side thereof, guide means for positioning a channeled stick slidably endwise in the guide means adjacent and parallel to part of said one side of the conveyor with the channel of the stick open toward the conveyor, gripping members movable along a path between the guide means and said part of the conveyor and adapted to seize intermediate projecting portions of the leaves on the conveyor and to propel their stem ends along the channel of a stick positioned by the guide means, a motor connected to drive the conveyor and gripping members in the same direction, a switch operable to stop the motor, and switch control means responsive to removal of a stick from the guide means to cause the switch to stop the motor.

5. Apparatus for loading the stem ends of tobacco leaves into a channeled stick, comprising a conveyor adapted to support tobacco leaves laid transversely across the conveyor with their stem ends projecting from one side thereof, guide means for positioning a channeled stick slidably endwise in the guide means adjacent and parallel to part of said one side of the conveyor with the channel of the stick open toward the conveyor, gripping members movable along a path between the guide means and said part of the conveyor and adapted to seize intermediate projecting portions of the leaves on the conveyor and to propel their stem ends along the channel of a stick positioned by the guide means, a motor connected to drive the conveyor and gripping members in the same direction, a switch operable to start the motor, and a switch operable to stop the motor and means responsive to removal of a stick from the means to operate the latter switch to stop the motor.

6. Apparatus for loading the stem ends of tobacco

leaves into a channeled stick, comprising a conveyor adapted to support tobacco leaves laid transversely across the conveyor with their stem ends projecting from one side thereof, guide means for positioning a channeled stick slidably endwise in the guide means adjacent and parallel to part of said one side of the conveyor with the channel of the stick open toward the conveyor, the guide means being open at one end to receive a stick thrust in endwise and at its other end having a stop member to abut the entering end of the stick, said stop member having a channel which generally parallels and opens toward the conveyor and which at one end is adapted to form an extension of the channel in the stick when the stick abuts the stop member, and at its other end is widened to gather in the stem ends projecting from the conveyor, gripping members movable along a path between the guide means and said part of the conveyor and adapted to seize intermediate projecting portions of the leaves on the conveyor and to propel their stem ends along the channel of a stick positioned by the guide means, said gripping members being positioned to initially seize the leaves adjacent said stop member, and means connected to drive the conveyor and gripping members in the same direction.

7. Apparatus for loading the stem ends of tobacco leaves into a channeled stick, comprising a horizontal conveyor adapted to support tobacco leaves laid transversely across the conveyor with their stem ends projecting from one side thereof, guide means for positioning a channeled stick adjacent and parallel to part of said one side of the conveyor with the channel of the stick open toward the conveyor, a pair of vertically spaced parallel chain guides mounted with the gap between them disposed between the guide means and said part of the conveyor, a pair of endless chains slidable along the respective chain guides and adapted to seize intermediate projecting portions of the leaves on the conveyor and to propel their stem ends along the channel of a stick positioned by the guide means, and means connected to drive the conveyor and the portions of the chains in the chain guides at the same speed in the same direction.

8. Apparatus for loading the stem ends of tobacco leaves into a channeled stick, comprising a horizontal conveyor adapted to support tobacco leaves laid transversely across the conveyor with their stem ends projecting from one side thereof, guide means for positioning a channeled stick adjacent and parallel to part of said one side of the conveyor with the channel of the stick open toward the conveyor, a pair of vertically spaced parallel chain guides mounted with the gap between them disposed between the guide means and said part of the conveyor, a pair of endless chains slidable along the respective chain guides and adapted to seize intermediate projecting portions of the leaves on the conveyor and to propel their stem ends along the channel of a stick positioned by the guide means, means connected to drive the conveyor and the portions of the chains in the chain guides at the same speed in the same direction, longitudinal members forming part of the stick guide means and vertically adjustable to accommodate the stick guide means to sticks of different channel widths, and means attaching one of the chain guides to said member so that the gap between the chain guides is adjusted automatically when the stick guide means is adjusted for sticks having different channel widths.

9. Apparatus for loading the stem ends of tobacco leaves into a channeled stick, comprising a conveyor having a horizontal surface adapted to support tobacco leaves laid transversely thereacross with their stem ends projecting from one side thereof, guide means for positioning a channeled stick adjacent and parallel to part of said one side of the conveyor surface with the channel of the stick open toward the conveyor surface, gripping members movable along a path between the guide means and said part of the conveyor surface and adapted to

5 seize intermediate projecting portions of the leaves on the conveyor and to propel their stem ends along the channel of a stick positioned by the guide means, means connected to drive the conveyor surface and gripping members in the same direction, and means with a vertical surface disposed in spaced parallel relation along a portion of said one side of the conveyor surface before it reaches said gripping members, said vertical surface being adapted to abut the stem ends of leaves laid on the conveyor surface and thus to align them to be received by the gripping members for loading into the channel of a stick positioned by the guide means.

10. Apparatus for loading the stem ends of tobacco leaves into a channeled stick, comprising a conveyor adapted to support tobacco leaves laid transversely thereacross with their stem ends projecting from one side thereof, guide means for positioning a channeled stick adjacent and parallel to part of said one side of the conveyor surface with the channel of the stick open toward the conveyor surface, gripping members movable along a path between the guide means and said part of the conveyor surface and adapted to seize intermediate projecting portions of the leaves on the conveyor and to propel their stem ends along the channel of a stick positioned by the guide means, means connected to drive the conveyor surface and gripping members in the same direction, said guide means being adapted to allow endwise sliding movement of a stick therein oppositely to said direction when the empty stick is being inserted and in said direction when the stick is being loaded and withdrawn, and a supporting surface positioned adjacent the end of movement of the conveyor surface to support the leaves which have had their stem ends loaded in the stick, while the stick is being withdrawn from the guide means.

11. Apparatus for mounting tobacco leaves for drying, comprising a conveyor adapted to support tobacco leaves laid transversely across the conveyor with their stem ends projecting from one side thereof, a stick having a channel extending along one side thereof, guide means positioning the stick adjacent and parallel to part of said one side of the conveyor with the channel of the stick open toward the conveyor, gripping members movable along a path between the stick and the conveyor and adapted to seize intermediate projecting portions of the leaves on the conveyor and to propel their stem ends along the channel of the stick, and means connected to drive the conveyor and gripping members in the same direction.

12. Apparatus for mounting tobacco leaves for drying, comprising a conveyor adapted to support tobacco leaves laid transversely across the conveyor with their stem ends projecting from one side thereof, a stick having a channel extending along one side thereof, guide means positioning the stick adjacent and parallel to part of said one side of the conveyor with the channel of the stick open toward the conveyor, the stick being slidable endwise in the guide means, gripping members movable along a path between the stick and the conveyor and adapted to seize intermediate projecting portions of the leaves on the conveyor and to propel their stem ends along the channel of the stick, and means connected to drive the conveyor and gripping members in the same direction.

13. Apparatus for mounting tobacco leaves for drying, comprising a conveyor adapted to support tobacco leaves laid transversely across the conveyor with their stem ends projecting from one side thereof, a stick having a channel extending along one side thereof, guide means positioning the stick adjacent and parallel to part of said one side of the conveyor with the channel of the stick open toward the conveyor, the stick being slidable endwise in the guide means, gripping members movable along a path between the stick and the conveyor and adapted to seize intermediate projecting portions of the leaves on the conveyor and to propel their stem ends along the channel of the stick, and means connected to drive the conveyor and gripping members in the same direction, said stick being of unitary

extruded metal construction of uniform U-shaped cross-section from end to end, with maximum thickness at the base of the U and with a pair of flanges formed at the terminal ends of the U, said flanges being turned toward each other and rigidly spaced apart for insertion of tobacco leaf stems across the entire gap therebetween.

14. Apparatus for inserting the stem ends of tobacco leaves into a slotted stick, comprising an endless belt having a horizontal upper reach mounted to support and convey tobacco leaves laid transversely across it with their stems projecting from one side of it, means supporting the belt for traveling movement and including a drive roller at one end and an idler roller at the other end of said upper reach of the belt, a pair of opposite chain guides mounted along one side of the belt parallel to and closely spaced from each other and from said side of the belt, a pair of endless chains slideable along the respective chain guides and spaced to grip the stems of said leaves therebetween, means mounting said chains for movement along said guides including a pair of drive sprockets for the respective chains mounted with their axes of rotation in the same vertical plane as the axis of rotation of the belt drive roller and also including a pair of idler sprockets for the respective chains each mounted at the same level as the drive sprockets for the respective chains and between the drive roller and idler roller of the belt, the said idler sprocket for the lower chain being spaced nearer the belt idler roller than the said idler sprocket of the upper chain, a motor and means connecting the motor to drive the belt drive roller and chain drive sprockets at speeds which equalize the rate of travel of the belt and chains, and a guide channel extending adjacent and parallel to the said chain guides and disposed with its channel opening along its length toward said side of the belt and toward the gap between the chains in the chain guides, said guide channel being open at one end adjacent said drive roller and drive sprockets to receive a channeled stick therebetween thrust endwise into the guide channel with the channel in the stick facing the gap between the chains, whereby the stems carried between the chains are propelled along the channel of the stick.

15. Apparatus for inter-mixing tobacco leaves in different containers preliminary to drying, comprising a conveyor with an elongated horizontal traveling supporting surface suitable for conveying tobacco leaves laid there-

5
10

across, the initial length of the conveyor surface adjacent the beginning of such travel being accessible for simultaneously placing tobacco leaves on the surface at successive places along said initial length, and loading means positioned along one side of a subsequent length of the supporting surface as it travels, said loading means comprising means for positioning a channeled stick to receive in its channel the stems of the leaves on the travelling surface, and means for seizing the stems and forcing them into the channel of such stick.

16. Apparatus for mounting tobacco leaves for drying, comprising a conveyor adapted to support tobacco leaves laid transversely across the conveyor with their stem ends projecting from one side thereof, a stick having a channel extending along one side thereof, guide means positioning the stick adjacent and parallel to part of said one side of the conveyor with the channel of the stick open toward the conveyor, the stick being slideable endwise in the guide means, gripping members movable along a path between the stick and the conveyor and adapted to seize intermediate projecting portions of the leaves on the conveyor and to propel their stem ends along the channel of the stick, means connected to drive the conveyor and gripping members in the same direction, and a member mounted at one end of the guide means and abutting one end of the stick, the abutting end of said member having the same cross-section as the stick and being mounted to form a continuation of the stick, and said stick being of unitary extruded metal construction of uniform U-shaped cross-section from end to end, with maximum thickness at the base of the U and with a pair of flanges formed at the terminal ends of the U, said flanges being turned toward each other and rigidly spaced apart for insertion of tobacco leaf stems across the entire gap therebetween.
